CLAIM

The ornamental design for a receptacle for a cordless portable telephone handset, as shown and described.

DESCRIPTION

FIG. 1 is a top, left, front perspective view of a receptacle for a cordless portable telephone handset showing our new design;

FIG. 2 is a bottom plan view thereof;

FIG. 3 is a rear elevational view thereof;

FIG. 4 is a right elevational view thereof; and,

FIG. 5 is a top elevational view thereof.

The broken lines shown in FIGS. 1-5 are for illustrative purposes only and form no part of the claimed designed.
